UNITED STATES PATENT OFFICE.

WILLIAM A. MYERS, OF SCRANTON, PENNSYLVANIA, ASSIGNOR OF ONE-HALF TO S. N. STETLER, OF SAME PLACE.

HYDRAULIC BRAKE.

SPECIFICATION forming part of Letters Patent No. 258,538, dated May 23, 1882.

Application filed March 23, 1882. (No model.)

To all whom it may concern:

Be it known that I, WILLIAM A. MYERS, a citizen of the United States, and resident of Scranton, in the county of Lackawanna and State of Pennsylvania, have invented a new and valuable Improvement in Hydraulic Brakes; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side view of my hydraulic brake, and Fig. 2 is a similar view enlarged.

The object of this invention is to provide a cheap and reliable brake for locomotives, constructed with parts so strong and simple that there will be no difficulty in keeping it in order and having it repaired by any ordinary mechanic.

The invention consists in the construction and novel arrangement of parts constituting a hydraulic brake, as will be hereinafter fully described, and particularly pointed out in the claims.

In the accompanying drawings, the letter A designates a pump, which is operated from the forward axle by an eccentric, D.

B represents a cylinder, in which works a piston, E, connected by the rod F to the angle-lever J of the brake.

C is a tank containing water or other liquid, and connected by a pipe, V, to the pump A, said pipe having a check-valve, Q', opening in the direction of the pump A. A pipe, W, also connects the tank to the pump, and is provided with a branch-pipe, W', leading to the cylinder B.

Q represents a three-way valve, which is located in the pipe W at its junction with the pipe W', and serves to close these pipes alternately to the water coming from the pump.

S represents a safety-valve on the pipe W', which is designed to regulate the pressure on this pipe, and also on the piston E. The pipe W' is also connected to the tank by a pipe, Y, which is provided with a cock, z, having a lever-arm, u, and operated by a rod, r, attached to said lever-arm and leading to the engineer's

cab. The three-way valve Q is also provided with a lever-arm, T, which is operated by a rod, r', also extending to the cab. The pipe W is also provided with a check-valve, Q''.

K indicates the brake-shoes, operating on the driving-wheels M.

L is the engine-frame; and P represents a box-bearing, which is bolted to the lower bar of the frame, and supports the rock-shaft or journal of the angle-lever J. The brake-shoes are connected at their lower ends by toggles G and at their upper ends by toggles G', the latter being pivoted to hangers H, which are secured to the engine-frame, and support the upper ends of the brake-shoes. The arm N of the angle-lever J extends over the toggle-joint, and is connected to the toggle G by means of a link, I. Connecting-rods F, usually made in sections, connect the angle-levers J and the piston-rod. The ends of the sections of these connecting-rods are threaded and joined by means of turn-buckles R, whereby the pressure of the brake-shoes on all the wheels is adjusted and equalized.

The operation of the brake is as follows: The tank C is filled with water, which flows into the pump A through the pipe V on the suction-stroke of the pump. On the return-stroke the check-valve Q' closes, causing the water to discharge through the pipe W back into the tank, the valve Q being open to that pipe. This operation continues during the movement of the engine, when the brake is not required to be put in action. When it becomes necessary to operate the brake the engineer closes the valve Q to the tank and opens it to the pipe W', leading to the cylinder B. As this pipe discharges the water back of the piston E, it forces said piston forward, and by the connecting-rod F draws on the brake-lever J, raising its arm N and connecting-link I, and thereby straightening out the toggles and forcing the brake-shoes against the wheels. As the brake-shoes are operated by toggles at their upper ends as well as at their lower ends, the pressure exerted by them is uniform throughout their extent or bearing-surface.

As a few strokes of the pump will suffice to fill the cylinder, it is necessary to have an escape, which is furnished by the safety-valve S.

s, which can be set to any desired pressure. The water escapes through the safety-valve by the pipe *x* into the tank.

In order to release the brake, the engineer 5 throws the three-way valve *Q* into its original position and opens the valve *z*, so that the water is allowed to pass from the cylinder *B* through the pipes *W'* and *Y* into the tank, the weight of the brake-shoes and their connections moving the piston *E* back to its original position.

The pump, cylinder, and tank are designed to be connected and bolted to a suitable attachment frame fastened to the frame of the 15 engine back of the smoke-box; or the engine may be built with a frame arranged to support the pump, cylinder, and tank.

A hydraulic brake has been combined with a locomotive-engine prior to my invention. A 20 sectional pitman provided with turn-buckles for adjusting the sections is also old, and double toggles have been used in connection with the brake-shoes of a locomotive-engine, and I claim neither of these devices, broadly, herein.

25 Having described this invention, what I claim, and desire to secure by Letters Patent, is—

1. In a hydraulic brake, the combination,

with the pump *A*, cylinder *B*, and tank *C*, of the pipes *V*, *W*, *W'*, and *Y*, the valves *Q*, *Q'*, 30 and *z*, the safety-valve *s*, and its return-pipe *x*, the eccentric on the axle of the engine, the piston *E*, rod *F*, the toggles *G* and *G'*, brake-shoes *K*, and the lever, arm, and link *J N I*, substantially as and for the purposes set forth. 35

2. In a hydraulic brake, the combination of the brake-shoes *K*, the toggles *G'*, secured to the frame *L* by the hangers *H*, the toggles *G*, the angle-levers *J*, having rock-shafts or journals on the engine-frame, the arms *N*, links *I*, 40 and rods *F*, and mechanism for operating them, substantially as specified.

3. In a hydraulic brake, the combination, with the pump *A*, cylinder *B*, and tank *C*, of the pipes *V*, *W*, *W'*, and *Y*, the valves *Q*, *Q'*, 45 and *z*, the safety-valve *s*, and its return-pipe *x*, and the eccentric on the axle of the engine operating the pump, substantially as specified.

In testimony that I claim the above I have hereunto subscribed my name in the presence 50 of two witnesses.

WILLIAM ALONZO MYERS.
